UNITED STATES PATENT OFFICE

2,136,941

ATTACHING AND PRINTING MACHINE AND
METHODCarl A. Flood, Framingham, Mass., assignor to
Dennison Manufacturing Company, Framing-
ham, Mass., a corporation of Massachusetts

Application August 20, 1935, Serial No. 36,989

23 Claims. (Cl. 93—88)

This invention relates to a combined printing and attaching machine, to a method of printing which is advantageously employed by this machine, and to features of printing and attaching mechanisms which are particularly useful in a machine of this type. My prior copending applications Serial Nos. 565,466 and 650,285, filed respectively September 28, 1931, and January 5, 1933, disclose machines of the general character to which the present invention is directed, these machines being arranged to print successive tickets with price markings and identifying indicia or the like, and to feed the printed tickets to an attaching station where each ticket may be attached to an article of wearing apparel or the like. Thus machines of this type are particularly suited for use in department stores, mail order houses and similar establishments.

In accordance with the present invention, a particularly convenient printing mechanism may be provided, having means to facilitate the adjustment of the impressing elements so that the indicia being printed upon the tickets can be readily changed. Thus the present invention adds to the utility of machines of this character, especially when small lots of tickets are to be printed. In many respects the printing mechanism may be of the type disclosed in my copending application Serial No. 695,116, filed October 25, 1933, such a mechanism providing a series of printing wheels and a corresponding series of indicating wheels, a suitable carriage being provided to permit the ready adjustment of any selected indicating wheel and the simultaneous corresponding adjustment of the printing wheel. Thus ready movement of the selected impressing elements to printing position may be effected without necessitating removal of the printing head from the machine or any operations that are likely to soil the hands of the operator of the machine.

The present invention particularly permits the employment of printing mechanism of this character to print at least two lines of printing in compactly spaced position. To this end, the printing wheel assembly may include two portions which successively engage the ticket being printed, so that one portion of the mechanism is effective in printing one line upon the ticket and the other portion of the mechanism is effective in printing an adjoining line. Furthermore, the invention also affords means so that this printing mechanism may be effective in duplicating each of the lines of printing on the ticket when desired.

To permit these desirable results, the ticket feeding means preferably is arranged to move the ticket into juxtaposition to the first portion of the printing mechanism, whereupon a printing operation is effected, and then to move the ticket into juxtaposition to the second portion of the mechanism when the second printing operation is effected. If the two lines of printing are to be duplicated, the feeding mechanism then moves the ticket back into juxtaposition to the first printing portion, where a third printing operation occurs and the first line is repeated. The ticket is then moved by the feeding mechanism into another location wherein it is juxtaposed to the second printing portion and is there again printed so that the second line of indicia is duplicated.

In order to facilitate these operations, the feeding mechanism is arranged to feed the tickets preferably in a strip along a straight-line path to a severing mechanism. From this mechanism the severed ticket may be fed transversely to one printing portion; then fed transversely, preferably back to a position in line with the path of movement of the ticket strip, to a second printing position; then transversely to a third printing position substantially in line with its first printing position; then transversely to a fourth printing position substantially in line with the second printing position. From this point the feeding mechanism may direct the ticket to the attaching station. The attaching mechanism may be of the general type disclosed in my above-identified application Serial No. 565,466, being arranged, for example, to pin the ticket to an article of apparel or the like.

One important feature of the present machine relates to the arrangement of control means effective to permit a single printing of each of the two lines of indicia upon a ticket or the duplicate printing of the two lines, and separate control means to control the feeding of the tickets so that either long or short tickets may be fed, as desired.

A further feature of the invention relates to the provision of means which is particularly advantageous with tickets of the type disclosed in my United States Patent No. 1,912,268, issued May 30, 1933, having recesses therein to receive the point of an attaching pin and guide the same to a position wherein it is embedded between the surfaces of the ticket. In accordance with this invention, recesses of this type may be taken advantage of to receive a feeding pawl or

finger which is effective in advancing successive tickets to the severing position.

A further advantageous aspect of the invention relates to the provision of control means which is to be employed when the machine is to be cleared of tickets of one type, this control means being arranged so that the printing mechanism may be temporarily rendered inoperative and the part of the feeding mechanism which directs tickets to the severing means may similarly be rendered inoperative, so that the last ticket proceeding from the printing mechanism may pass to the attaching station and be attached without necessitating the printing of an extra ticket or without necessitating the direct engagement of a portion of the ticket-supporting means with the printing wheels. Furthermore, this control means may be arranged so that the strip carrying the pins is not advanced following the application of a pin to the last ticket of the series. Consequently, when the printing of a new set of tickets is initiated, a pin will not be advanced to the attaching station at a time when no ticket has arrived at that station. When the first printed ticket of the new series reaches the station, the strip has again advanced one step to bring a pin into proper position for attaching the first printed ticket of the new set. Thus jamming of unused pins in the attaching mechanism is avoided and unnecessary wasting of pins is eliminated.

Cooperating with this arrangement is the general arrangement of the mechanism so that while one ticket is passing through the printing cycle, the preceding ticket is being attached to the article of apparel or the like. Thus, ample time is provided for the operator to dispose and adjust a garment or the like in a position to have a printed ticket attached thereto while the printing operations are being performed on the succeeding ticket.

Further advantageous features of the invention relate to the provision of the cam and linkage arrangements and the structural and mechanical details which permit a simple, compact, and dependable mechanism of this character to be provided, despite the multiplicity of movements imparted to the ticket as it passes through the machine.

Fig. 23 is a detail view showing the feeding pawl arranged to feed short tickets.

Referring to the accompanying drawings, which illustrate a machine exemplifying the principles of this invention, the numeral 1 designates a frame having a suitable base 2 with an upright skeletonized wall portion 3 adjoining the front of the machine. The frame also includes a table-like upper plate 4 having certain parts cut 30 away for purposes which will be described. In practice the machine is provided with a removable rear wall portion 5, and certain detachable covering plates (not shown) which may be disposed between the base 2 and the table portion 4. 35

A machine of this character is provided with a driving motor 10 which may be constantly operating when the machine is in use. Worm gearing, driven by the motor, may be effective through a one-revolution clutch mechanism 17 in driving 40 the main shaft 18. The worm gearing is disposed in a casing 15 which also aids in supporting table 4. The clutch mechanism 17 is similar to that disclosed and described in my copending application Serial No. 565,466 and includes a 45 pawl 19 which may be effective in causing the notched wheel 20 to drive the disk 21 on the end of shaft 18 whenever control block 22 is moved rearwardly out of the path of the pawl. For this purpose a plate 23, located at the front of the 50 machine and connected to the control block 22 by a slid rod 24, may be pressed inwardly to move the block momentarily out of the path of the pawl. Thereupon the member 23 may be released by the operator so that block 22 returns 55 to its normal position and is effective in stopping the pawl 19 and disengaging the latter from the wheel 20 at the conclusion of one revolution of the shaft. The details of such a clutch mechanism are fully disclosed in my copending application 60 Serial No. 565,466.

The shaft 18 is provided with a cam disk 30 disposed in front of the housing for the worm gear assembly. Referring to Figs. 6 and 7, it is evident that the disk 30 is of irregular contour 65 and that its periphery engages a follower 31 on the end of an arm 32 pivoted to a bracket that is fixed on the base 2 of the machine. A tension spring 33 normally tends to pull the arm 32 and follower 31 upwardly, thus holding the latter in 70 yieldable engagement with the edge of the cam disk. The arm 32 is part of a bell crank assembly that includes the upwardly extending arm 35 which is connected by a short link 36 to ears 38 depending from a block 39 which is fixed on a rod 75

37 that is slidable in a housing 34 fixed to the table portion 4 of the frame; see Fig. 6.

As shown in Figs. 2 and 6, an extension 40 of the block 39 projects between two parallel guide bars 42 and 43 at one side of housing 34 and carries a bracket pivotally supporting feeding pawl 46. A coil torsion spring 45 normally urges the front end of the pawl downwardly, this portion of the pawl being provided with a pointed feed finger or prong 49. As shown in Figs. 4 and 23, the pawl is provided with a pair of notches which permit its adjustment relative to the stud 40 so that the prong 49 may be disposed nearer the front of the machine, i. e., farther away from the stud, when a long ticket is to be fed, or may be disposed closer to the stud when a short ticket is to be fed.

The tickets may conveniently be received from a strip S which is arranged to provide a coil in a magazine 58 (Fig. 1) at the top of the machine in the manner already described in my copending application Serial No. 565,466. From the coil, the strip S extends between the inner and outer sheet metal guide ribbons 52 and 53 to a position above the table 4, the metal ribbon or strip 52 extending to a position beside the housing 34 (Fig. 2). Thus when the prong 49 moves toward the rear of the machine, it engages the front edge of the strip 52 with a cam-like action and moves out of engagement with the ticket strip. When the prong moves toward the front of the machine, it slides over the strip 52 until it reaches the edge of the latter, whereupon the spring 45 presses the pawl downwardly to engage the ticket which projects beyond the end of the metal strip.

Preferably a machine of this type may employ tickets T of the character disclosed in my United States Patent No. 1,912,268, which, as shown in Fig. 15, may be formed of two laminae as by folding the intermediate portion of a sheet back upon itself and securing the folded portions together, one of the sheet portions having an opening to provide a recess R in the ticket. The feeding prong 49 may engage these recesses in successive ticket sections and may move the same forwardly in response to the forward movements imparted to the member 39 and the rod 37 by the bell crank 32-35.

50 A guide track 60 (Figs. 2 and 7) is provided with a cross member 58 which extends over the member 52 to hold the latter in position above the table 4. This track comprises a lower plate upon which the tickets or ticket strip may slide and side members 61 and 62 which have small rabbets therein to receive the edges of the ticket. A spring of resilient sheet metal, designated by numeral 65, is secured to the front end of track member 62 and is arranged so that its forward extremity may press downwardly on the ticket strip adjoining a cutter 78, the latter being arranged to cooperate with a slot between the front of the table 4 and the adjoining edge of the platen plate 91 to afford a shearing action.

65 A cam 75 is fixed to the main shaft 18 adjoining the cutter, being provided with cam portions upon each of its faces. Referring to Fig. 3, it is evident that the cam member 75 is provided with an inner cam groove 76 in which a follower roller 77 is received. This roller is mounted on a swinging bracket 78, to the intermediate part of which a link 80 is articulated. The upper end of the link 80 is pivotally connected to a block 82 (Figs. 1 and 2) which is pivoted on a fixed bracket 83 secured to the corner of table portion

4 of the machine. A cutting plate 85 is secured to the block 82 and provides an inwardly extending blade portion 70 which registers with the slot provided between the front edge of the table 4 and the platen plate 91. Thus as the cam 75 is rotated, it is effective through the cam groove 76, follower 77, members 78 and 80 in causing the cutting blade 70 to move downwardly into the slot, thus to sever a ticket T from the strip S.

After a ticket has thus been severed, it is disposed beyond the end of the track 60 and is located in a track 90 on the plate 91, this track 90 being provided with grooved portions which may be aligned with the guide rails 61 and 62 of the track 60 (Fig. 2). Disposed over the rear part of the track 90 is a small guide member 95 which prevents the ticket from bulging upwardly and holds it in engagement with the bottom of the track.

The platen plate 91 is transversely reciprocated by a swinging bracket assembly 100 (Figs. 3 and 6), which is pivotally mounted on the lower part of the frame. The assembly 100 comprises an inwardly extending arm 101, indicated in dotted lines in Fig. 3, and having a follower roll 103 engaging the cam groove 104 upon the back of the cam member 75, this cam groove also being shown in dotted lines in Fig. 3.

A suitable supporting block 110 is arranged to provide a guide for the platen plate 91 (Fig. 4) so that the latter may have a transverse movement imparted thereto by the cam groove 104. The front face of cam member 75 is provided with an outer cam groove 140 (Fig. 3) which determines the up-and-down movement of the platen plate 91. For this purpose the plate assembly is provided with a follower roll 141 engageable in the groove 140. This groove 140 is provided with inner and outer portions 140^a and 140^b, as particularly shown in Fig. 8. The inner portion of the groove provides four throws so that four up-and-down movements of the platen plate may result from one revolution of the main shaft when the follower 141 is in this part of the groove. The outer part 140^b of the groove has two throws so that only two up-and-down movements of the platen plate occur when the roller is engaging this outer part of the groove.

To permit ready movement of the follower from one to the other of these groove portions, it is disposed on the end of a slidable cylindrical support 148 carried by member 110 and having a depending stud 149 engaging the slotted end of an arm 150 which has a pivotal connection 151 with the block 110 (Fig. 17). The opposite end of arm 150 is also slotted and receives the down-bent end 156 of a control rod 157 that is connected to a control knob 160 (Fig. 2) projecting upwardly from the table 4. Thus when the knob 160 is moved rearwardly, the roller 141 may engage the groove portion 140^b, while when the knob is moved forwardly, the roller may engage the cam portion 140^a, it being evident that a slot 161 limits the path of movement of the control knob 160, and that in the position in which the parts ordinarily stop, as determined by the one-revolution clutch mechanism, the follower 141 may move from one portion of the cam groove to the other, since in this position these portions have similar cross sections and in effect form one deep groove. A spring-pressed ball 153 may normally engage one of two recesses 154 in the upper surface of arm 150, thus tending to hold the arm, the rod 157 and knob 160 in one or the other of the two selected positions so that the

follower 141 is definitely located either in the cam groove portion 140^a or 140^b.

The front end of rod 37 is provided with a stirrup portion 115 (Fig. 2) having a transverse slot 116 receiving a pin 117 upon the swinging feed finger 118 which is pivotally connected to an arm 119 extending from the right-hand end of the platen plate 91. The finger 118 has a forwardly curved or inclined end portion 120 which slides over plate 91, and it has a part engaging an arcuate guide groove 121 formed in a part of the platen plate (Fig. 22). The finger 118 has a composite movement which results from the reciprocatory movement of the rod 37 and stirrup 115 and from the transverse reciprocating movement of the platen plate 91. Thus after a ticket has been severed, the member 118, as will be more fully explained, may be effective in advancing the ticket to successive printing positions on the platen plate as the latter is reciprocating transversely and may finally advance a ticket from the last printing position to the attaching station.

The platen plate 91 is provided with similar inset inking pads 170 which are disposed on opposite sides of the track assembly 90. Above this portion of the platen plate is the printing wheel assembly, designated in general by numeral 200. This assembly has a pivotal connection 201 (Fig. 3) with a bracket 202 secured to the frame of the machine. A suitable ear 203 (Fig. 1) projects from the opposite end of the assembly 200 to engage a fixed portion of the machine, normally being held by a spring 204 and retaining nut 205 in engagement with a cam plate 206. Thus the ear engages the cam plate to limit the downward movement of the free end of the assembly 200 so that the latter will not rest upon the platen plate when the latter is in its normal position, i. e., when the track portions 60 and 90 are coplanar. When the printing wheel assembly occupies this position, it has a slight inclination upwardly toward the left side of the machine, as seen, for example, in Figs. 3 and 10.

The printing wheel assembly itself may be of the type disclosed and claimed in my United States Patent No. 1,980,576, issued November 13, 1934, and provided with certain improvements disclosed in my copending application Serial No. 695,116, filed October 25, 1933. Since the details of an assembly of this character are fully described in the above-identified patent and application, which are included herein by reference, the description of these details will not be repeated herein.

However, for purposes of understanding the present invention, it may be pointed out that the assembly includes an outer, generally cylindrical casing 210 having an opening 211 therein with a transparent closure 212 of cellulosic material (Fig. 16). Disposed within this part of the casing are two sets of indicating wheels 214 and 215 (Fig. 3). The end of the assembly above the inking pads is provided with corresponding sets of printing wheels 224 and 225. The corresponding printing wheels and indicating wheels may be interconnected by mechanism of the character fully disclosed in the above-identified application and patent, so that, when a selected indicating wheel is moved into a position wherein a desired character registers with the upper end of a pointer bar 226 (Fig. 16), the corresponding character upon the corresponding printing wheel is disposed in a printing position, i. e., in the lowermost position upon the wheel. The assem-

bly is provided with a sliding carriage 227 having a control knob 228 which is operatively connectable with the wheel registering with the end of the pointer so that that wheel may be rotated to the desired adjusted position and the corresponding printing wheel simultaneously adjusted.

Suitable locking and releasing controls to facilitate longitudinal movement and adjustment of the carriage are provided at the left-hand end of the assembly 200. These parts are similar to those shown in my prior application Serial No. 695,116 and include a lower finger lever 230 which may be actuated to control ratchet mechanism effecting a step-like movement of the carriage to bring the wheels successively into operative connection with the control member 228, while the upper finger lever 231, when depressed, releases the ratchet mechanism to permit the free sliding movement of the carriage when it is desired to move the same readily to engage a wheel remote from the previously engaged wheel so that the newly engaged wheel may be adjusted.

It is evident that each time that the platen plate moves upwardly, it may press a ticket against one or the other of the printing portions of the assembly 200 which are provided respectively by the wheels 224 or 225. Thus when the platen plate is in a position so that the track portions 60 and 90 are in alignment, i. e., the ticket to be printed is in alignment with the ticket strip, the ticket may move upwardly to engage the wheels 224, as illustrated, for example, in Fig. 12. If the platen plate 91 has reciprocated to the other end of its path, it may move upwardly so that the ticket engages the wheels 225, as shown in Fig. 10. When the follower 141 is engaging the cam groove portion 140^b so that the platen plate moves upwardly four times during one cycle, i. e., during one revolution of the main shaft 18, the ticket may first engage the wheels 225. The platen plate may then be lowered and the finger 118 advances the ticket slightly so that the ticket is positioned to permit the printing of a succeeding line of indicia by the wheels 224. The platen may then return to the right-hand end of its path, the finger 118 again slightly advancing the ticket so that the first line of printing is duplicated by engagement of the ticket with wheels 225. Thereafter the platen plate may return to its original position, while the finger 118 again slightly advances the ticket so that the second line of printing may be duplicated during the fourth printing operation when the ticket again engages the wheels 224. Thereafter the platen plate remains in its normal position, while the finger 118 advances to the position shown in Fig. 9 to feed the ticket to the attaching station.

In general the attaching mechanism may be similar to that disclosed in my prior above-identified application Serial No. 565,466. In the manner more fully disclosed in that application, the pins are mounted on a paper strip M which provides a coil received in the right-hand side of magazine 50 and has a run extending downwardly in the curved channel-like chute 300 shown in Fig. 1. The strip M preferably is weakened along a central longitudinal line and thus is substantially folded as it passes between the converging edges of guiding means 306 (Fig. 19). From the attaching station where successive pins are removed from the strip, the folded strip extends to the bite of rollers 307 and 308, one of which is provided with a notched wheel 309 to be actuated by the pin-inserting mechanism so that each

time that a pin is inserted the strip is drawn forward one step corresponding to the spacing between successive pins.

The severed and printed ticket as it moves forwardly out of the track 90 passes into a guide 311 (Fig. 2) and moves to a position beneath a downwardly extending beak 312 and above the point of an upwardly curved cusp 303, the inner longitudinal edge of the ticket being yieldably urged against a fixed shoulder 316 by a spring-pressed member 314 which engages its opposite longitudinal edge. Below the member 314 and the beak 312 is an upwardly movable anvil 320 having a spring-pressed plunger 321 and which is grooved to guide a pin as it is being inserted in material disposed on the anvil.

The main shaft 18 is provided with a cam 325 which has grooves upon its front and rear faces, the rear groove engaging a follower upon a bell crank 326 providing an upwardly extending arm 330 which has a pin 327 extending through a vertical slot 328 in a plunger rod 329 (Figs. 16 and 18). A wire plunger 340 extends from this rod and is movable to engage the head of a pin which is positioned in alignment therewith.

The front of cam 325 is provided with a cam groove engaging a follower 332 (Fig. 16) on the end of an arm 333 which is pivoted at 339 to a fixed bracket. The opposite end of the arm 333 is connected by a coiled tension spring 341 to the end of an arm 343, the intermediate part of which is pivoted to the arm 333 between the follower 332 and its pivotal connection 339. The outer end of arm 343 is pivotally connected to the vertically movable anvil 320 which reciprocates vertically in the boss 344 at the front of the machine. The top of the anvil is provided with a groove into which the pin may move as it is being advanced by the plunger 340.

The plunger rod 329 reciprocates between the front and rear walls of a guide plate assembly 350 (Fig. 20), the rear wall of this assembly being cut away to provide a slot 352 (Figs. 20 and 21) through which the pin 327 extends. Held against the back of this wall of the assembly by an angle 359 and a sliding member 365 is a sliding bar 355 which is also provided with a slot 362 through which the pin 327 extends, the slot 362 being, however, of less length than the throw of pin 327 so that as the pin approaches the right-hand end of its path, as viewed in Fig. 20, the bar 355 also is moved slightly toward the right, the tension spring 358 normally holding the bar out of this position. At the left-hand end of the bar 355 a slot 360 is provided to receive a pin 361 secured to the beak 312. A suitable spring-controlled pawl 364 is connected to the end of bar 355 and may engage the teeth of ratchet wheel 309, so that, during each reciprocation of the bar in response to a movement of pin 327, the wheel is rotated through an angular distance corresponding to one of its teeth, thus causing the folded strip M to be drawn away from the attaching station by a stepped movement corresponding to the spacing between successive pins.

The bar 365 is slidably mounted behind the bar 355 and is connected by a tension spring 366 with a fixed part of the machine. The bar 365 is provided with a slot 367 to accommodate the pin 327. This slot, however, is dimensioned so that each time the pin approaches the end of its path, it engages the end of the slot and moves the bar 365 to the right, as viewed in Fig. 20. When the actuator pin 327 moves toward the left as viewed in Fig. 20, the spring 366 moves bar 365 toward

the left, the latter being effective through connection 361 in swinging the beak 312 downwardly to the position shown in Fig. 19. When the pin 327 approaches the right-hand end of its path, it moves the bar 365 in the same direction, thus being effective to swing the beak to its retracted position.

The normal operation of the attaching mechanism results from the oscillating movement of the pin 327 and the vertical movement of the anvil 320 to the attaching station. Thus during each cycle of the machine the pin 327 moves toward the attaching station, while the anvil 320 also moves toward the station. As the movement of the pin is started, the bars 355 and 365 also move in the same direction, the latter being effective in causing the point of beak 312 to project into the recess R of the ticket to spread the plies of the ticket.

In the meantime the anvil 320 has moved upwardly to bend the ticket to the shape shown in Fig. 19, whereupon the rod 340 engages the head of a pin so that its point passes through the bent ticket and below the lower surface thereof to pass into the sheet article A or the like, then again passing through the article and through the ticket, its point being then guided by the beak into the space between the plies of the ticket so that the point becomes embedded within the ticket.

As the pin 327 starts to move away from the attaching station, the anvil 320 moves downwardly and as the pin 327 approaches the end of its path, it engages the bar 365 to cause the retraction of beak 312, whereupon the ticket is released to be withdrawn with the sheet article A. During this same part of the cycle, the pin 327 is also effective in moving the bar 355 toward the ratchet wheel 309, the pawl 364 thereupon being effective in moving the corresponding roller 308 one step, so that the strip M is drawn forward to bring another pin into alignment with the plunger 340.

Means are provided so that the printing mechanism may temporarily be rendered ineffective and so that the means for driving the rollers 307 and 308 may be temporarily interrupted when it is desired to stop printing one lot of tickets and start printing another lot. The cam plate 206 is effective for this purpose, this plate being pivotally mounted on a vertical stud 207 upon which the nut 205 is screwed. Member 206 is provided with recesses 213 in which cam-like protuberances 208 on the ear 203 of the printing assembly 200 are normally received, the spring 204 tending to hold these parts in engagement.

In its normal position the cam plate 206 does not affect the operation of the machine. However, it may be swung to the position indicated in dotted lines in Fig. 2 and shown in Fig. 20 to block the path of the bar 355. When the plate is swung to this position, it also lifts the printing end of the printing assembly 200 slightly above the normal position, as shown in Fig. 4, so that the pads 170 do not engage the printing wheels when the assembly is tilted upwardly to this position.

Extending rearwardly from the casing of the assembly 200 is an arm 216 which provides a horizontal flange 217 engageable with a pin 218 projecting from the side of feed pawl 46. Thus, as shown in Fig. 4, when the cam plate 206 is in a position to block the sliding rod 355, the flange 217 is effective in holding the pawl 46 in a posi-

tion so that the prong 49 does not engage a recess in the ticket strip. Accordingly feeding of the tickets in this portion of the machine is interrupted, the engagement of a ticket with the printing wheels or engagement of the platen with the same is also prevented, and the strip M is not being withdrawn by the rollers 307 and 308. However, the feed finger 118 can continue its movement so that a printed ticket may be advanced to the attaching station and the pin 327 is still effective in actuating the plunger rod 329 and the plunger 340 so that a pin, which has already moved into a position in alignment with the plunger, may be forced into the last ticket 15 of the series.

Thereupon the printing mechanism may be adjusted to print a new lot of tickets and the cam plate 206 be returned to its normal position. This permits the pawl 46 to resume its normal 20 position and the printing assembly to return to its normal position. Accordingly the pawl may be effective in feeding a ticket to the cutter 70 and the printing mechanism may then print the ticket. At this time, however, there is no ticket 25 in the vicinity of the attaching station; the plunger 340, however, is reciprocated, but it does not engage a pin, since the strip M was not advanced during the preceding cycle, and there is no liability of a free pin becoming jammed in the 30 mechanism and the wasting of a pin is avoided. As this first cycle of the new series ends, however, the rollers 307 and 308 are again actuated to draw the pin strip M forwardly one step, so that, at the end of the first cycle, another pin is 35 disposed in proper position to be pushed by the plunger 340 during the second cycle when the first printed ticket of the new series reaches the attaching station.

When a machine of this character is being 40 used, the motor 10 may be constantly operating so that the notched wheel 20 is constantly being driven. The operator of the machine may dispose an article such as a garment over the upper end of anvil 320 and may simultaneously push 45 the control plate 23 inwardly for a moment. This is effective in moving the control block 22 out of engagement with the pawl 19 so that the latter engages notched wheel 20, i. e., clutch 17 is engaged, and the disk 21 and main shaft 18 50 start rotating. As soon as the plate 23 is released, the block 22 moves back into the path of the pawl so that the main shaft is stopped as soon as one revolution is completed. In other words, the momentary pressure which pushes the 55 plate 23 rearwardly causes the main shaft to rotate through one revolution.

When the cycle of operations starts, the prong 49 of pawl 46 may be disposed slightly behind a recess R in one of the ticket sections, for example, in the position shown in Fig. 2. As the cycle starts, the cam disk 30 is positioned to actuate the follower 31 which is operative through the arms 32 and 35 in causing the rod 37 to move forwardly, thus moving the pawl 46 forwardly, 60 the end of this pawl being pressed downwardly by the torsion spring 45. The prong 49 accordingly engages the recess R in the ticket section which adjoins the end of the metal ribbon 53.

As the forward movement of the bar continues, 65 a ticket section which is directly ahead of the section being engaged by prong 49 passes beneath the cutter 70. The cam disk 30 is shaped so that the rod 37 and pawl 46 hesitate at the forward ends of their paths while the cutter 70 starts 70 severing the first ticket section from the strip.

As previously described, the cutter is actuated by the inner cam groove at the front of cam 75, which is effective through swinging bracket 78 and link 80 in swinging the cutter downwardly into the slot between the front of table 4 and the platen 91, the latter remaining stationary during this cutting operation.

As the severing movement of the cutter 70 is continued, the pawl 46 starts moving rearwardly and this movement is continued as the platen plate 91 starts to move transversely out of its normal position, i. e., out of the position wherein the tracks 60 and 90 are in alignment, thus moving the severed ticket beneath wheels 225. This transverse movement of the platen plate is determined by the cam groove 104 at the back of cam 75, this cam groove being effective through arms 101 and 100 in causing the sliding movement of the platen plate on the guide block 110; see Figs. 10, 11 and 12. At the end of its transverse path 20 the platen plate may be swung upwardly by one of the throws on cam groove 140, which acts through follower 141 and member 110 in lifting the platen plate so that the ticket is pressed upwardly into engagement with the printing wheels 225, i. e., the right-hand set of printing wheels 25 as shown in Fig. 10.

It is evident that the inclined position of the printing assembly permits the movement of the ticket in a direction which is substantially normal to the planes of the surfaces of the printing elements on the wheels, as shown in Fig. 10. As this first printing operation occurs, the pad 170 at the outer end of the platen block engages the printing wheels 224 to ink the same.

Following this first printing operation, the platen moves downwardly and then transversely as determined by the cam grooves 140 and 104, respectively, so that it returns to its original position. During this transverse movement, the feed finger 118, which is actuated by rod 37, moves forwardly so that the ticket which is being printed is advanced for a distance corresponding to the spacing of the lines of printing. When the platen reaches its normal position, the cam groove 140 may again cause the platen to move upwardly so that the ticket engages the printing wheels 224, as shown in Fig. 12, thus performing the second printing operation. While this is being done, the wheels 225 are being inked by the pad 170 at the right of the guide track 90.

Following this, the platen 91 may again move transversely while the feeding finger 218 again advances the ticket slightly so that a blank portion thereof may be positioned for the printing of another line of indicia, which will duplicate the first line. Thereupon the platen may again be swung upwardly to the position illustrated in Fig. 10, wherein the printing wheels 225 are effective in making another impression and the wheels 224 are again being inked.

After the platen moves downwardly following this operation, it is again moved transversely and the feed finger 218 again advances the ticket slightly, whereupon the platen, upon reaching its normal position, may again move upwardly so that the fourth printing operation is effected by engaging the ticket with the printing wheels 224, and the wheels 225 are simultaneously inked by the pad at the right of the guide track. 70

When the ticket has moved this far, the one-revolution clutch mechanism 17 normally disengages, leaving the printed ticket in the track 90. When the plate 23 is again actuated, the advance movement of rod 37, which causes the 75

pawl 46 to move a ticket section forwardly to the cutter, also causes a very substantial forward movement of the feed finger 118 to feed the ticket to the attaching station (Fig. 9). The 5 feed finger 118 is retracted while the next ticket section is being severed and while the first printing operation occurs, so that the finger is positioned to engage the rear end of the ticket which has just received the first impression as the 10 platen returns to its normal position following the first printing operation.

Fig. 13 particularly illustrates the path and various positions of a ticket as it passes through the printing cycle in the manner just described, 15 the heavy arrows indicating the paths of the center of the ticket, and various dotted line positions of the feed finger 118 being shown when this finger is at the beginning of one of its advance movements. While in Fig. 13 the ticket 20 path is illustrated as including straight-line, diagonal portions, it is evident that in practice the ticket may move slightly in a transverse direction before the cam controlling feed finger 118 actuates the latter to cause an advance movement. 25 It is evident that at each of the positions of the ticket illustrated in Fig. 13, except the view shown in full lines at the upper left-hand portion of that figure, the ticket is in a printing position. In other words, at the end of each transverse path 30 the ticket is moved upwardly and printed.

While one ticket is being subjected to successive printing operations in the manner already described, the preceding ticket, which has been fed to the attaching station by the substantial 35 forward movement of the feed finger, receives the fastening pin in the manner described in connection with the operation of the pinning mechanism. When the anvil 320 moves downwardly while the printing portion of the cycle 40 for the succeeding ticket is taking place, the garment or the like with the ticket pinned thereto may be removed from the machine.

When it is desired to have the machine print only twice, the control knob 160 is moved to its 45 rearmost position so that the member 150 is swung to pull the cam follower 141 out of the portion 140a of the cam groove 140 (Fig. 8) into the portion 140b which has only two throws. When the parts are in this position and the plate 50 23 is pushed inwardly to cause engagement of the clutch 17, the parts may follow the same general cycle as has been described, with the exception of the fact that the platen plate 91 is not moved upwardly following two of its transverse 55 movements. Thus, for example, the plate may not move upwardly the first time the ticket is disposed under the printing wheels 225 or the first time that the ticket has returned to a position under the printing wheels 224.

60 When the ticket is again returned to a position under the wheels 225, the first printing operation may be effected at a portion of the cycle corresponding to the third printing operation previously described. When the ticket is again 65 returned to a position in alignment with the track 60, a second printing operation may be performed during the part of the cycle corresponding to the fourth operation previously described.

As previously explained, when it is desired to 70 start printing different indicia, special means is prepared to take care of the last ticket of the series which has been printed. This last printed ticket is disposed on the track 90 at the end of the cycle. Before the final cycle, the cam plate 75 206 is then swung to the position indicated in

dotted lines in Fig. 2, so that the feeding pawl 46 is rendered inoperative, the printing assembly 200 is disposed in a position where it is out of the path of the platen, and the rollers 307 and 308 are not effective in drawing the strip M forwardly. The plunger 340, however, operates during the last cycle to cause a pin to engage the last printed ticket which has been advanced by the long forward movement of finger 218 to the attaching station. 10

Following this operation, the relative position of the printing wheels may be adjusted by the knob 228 until the desired combination of indicia is aligned with the end of pointer 226, and the cam plate 206 may be returned to normal position. Thereupon another cycle may be started by pressing the plate 23 inwardly. During this first cycle of the new series, there is no ticket in the attaching station and there is no reason for disposing an article in a position to receive 20 a tag. The foremost ticket section, however, is severed and moved to printing position and printed during this cycle, while the strip M is again drawn forwardly to bring another pin into alignment with the plunger 340 so that when the 25 second cycle is to be effected, a garment or the like may be disposed over the anvil 320 as the plate 23 is pressed inwardly and the first printed ticket of the new series may be advanced to the 30 attaching station by the long forward movement 35 of finger 118. The operation of the machine during this second cycle may thus proceed in the normal manner.

It is evident that this invention permits the 35 employment of a printing wheel assembly having two sets of printing wheels which may readily be adjusted and that the ticket is moved to a plurality of printing positions to engage these two sets of wheels, although the ticket itself may be small in size and the printing assembly may 40 be relatively bulky. Furthermore, this arrangement permits the duplicate printing by each of the sets of wheels. During the printing portion of the cycle there is a relative transverse movement between the printing mechanism and the 45 ticket between successive impressions. Thus the ticket in general may be regarded as following a zigzag path. It is furthermore evident that the mechanism may be readily adjusted to print only twice, i. e., to print two lines without duplication, and that the mechanism may feed and print short tickets. Furthermore, the machine operates so that ample time is afforded for the operator to locate an article in proper position for the attachment of the ticket and to permit 50 the attachment of the ticket to the article while the succeeding ticket is subjected to the printing operation. In fact, the pinning operation may be completed well before the end of the cycle so that ample time is given the operator 55 to place a new article over the anvil by the time the cycle has finished. Accordingly the cycles may be caused to occur in rapid succession. With such an arrangement, it is desirable to have special means to take care of the last ticket of a 60 lot having one type of indicia thereon, and for this purpose the cam plate 206 is effective to prevent the engagement of the printing wheels and platen without a ticket thereon, while the 65 wasting and possible jamming of an unused pin 70 is avoided and the feeding of the ticket strip is temporarily interrupted.

The inking of the printing elements on one set of wheels obviously is effected while the other set of wheels is performing an inking operation 75

so that no extra movements or mechanism is required to ink the printing elements. It is evident that, if desired, the platens 170 may be provided with different colors of ink so that one line of printing may be in one color and the next line have a different or contrasting color. The pivoted arrangement of the printing assembly permits it to be swung upwardly when the nut 205 is removed, thus facilitating cleaning of the printing wheels and access to the platen plate for cleaning or the like.

It is furthermore evident that the wheels 225 may be adjusted so that blank portions of the same are disposed over the platen so that these wheels will not be effective in printing. When the wheels are set in this manner, the ticket is advanced under wheels 224, being printed either once or twice by the same, depending upon the adjustment of the handle 160, and thereafter being advanced to the attaching station. Accordingly under these conditions the ticket may be fed along the track 60 onto the part of the platen which is normally aligned with the track, being printed due to the upward movement of the platen, and then after said part of the platen has returned to its normal position being advanced to the attaching station, which is substantially in alignment with the track and said part of the platen.

30 It should be understood that the present disclosure is for the purpose of illustration only and that this invention includes all modifications and equivalents which fall within the scope of the appended claims.

35 I claim:

1. A machine of the class described comprising ticket feeding means and including a platen, printing means including two sets of adjustable printing wheels arranged so that the wheels of one set are parallel to but out of the planes of the wheels of the other set, and operating mechanism for said feeding means arranged to cause the latter to direct a ticket into engagement with one of said sets of wheels and then move the ticket along a generally transverse path and into engagement with the other set of wheels so that the two sets of wheels print adjoining portions of the ticket.

2. A machine of the class described comprising ticket feeding means and including a platen, printing means including two sets of adjustable printing wheels arranged so that the wheels of the first set are parallel to but out of the planes of the wheels of the second set, and operating mechanism for said feeding means to cause the latter to direct a ticket into engagement with the first set of wheels, to cause the feeding means then to direct the ticket along a generally transverse path into juxtaposition to the second set of wheels while imparting a component of movement to the ticket parallel to its first path, and thereupon to cause said means to move the ticket into engagement with said second set of wheels, whereby the two sets of wheels respectively print successive lines upon the ticket.

3. A machine of the class described comprising ticket feeding means including a movable platen assembly having a ticket supporting portion, operating mechanism for said feeding means, printing means including two sets of printing wheels arranged side by side, said platen assembly being movable toward one of said sets of wheels so that a line is printed on a ticket by said wheels, the assembly then being movable away from said set of wheels along a transverse

path toward the other set of wheels while the feeding means also operates to impart a component of movement to advance the ticket along a path at right angles to said transverse path, the platen assembly thereafter moving toward 5 said other set of wheels to cause a second line to be printed on the ticket.

4. A machine of the class described comprising ticket feeding means including a movable platen assembly having a ticket supporting portion, operating mechanism for said feeding means, printing means including two sets of printing wheels arranged side by side, said platen assembly being movable toward one of said sets of wheels so that a line is printed on a ticket by said wheels, the 15 assembly then being movable away from said set of wheels and along a transverse path toward the other set of wheels while the feeding means also operates to impart a component of movement to advance the ticket along a path at right 20 angles to said transverse path, the platen assembly thereafter moving toward said other set of wheels to cause a second line to be printed on the ticket, said assembly having inking pads at each side of its ticket supporting portion so that 25 one pad is effective to ink one set of wheels while the assembly moves upwardly to cause printing by the other set of wheels.

5. A machine of the class described comprising a printing means including two printing portions arranged side by side, a platen having a part to support a sheet article and having two inking pads arranged respectively at opposite sides of said part, and means to cause movement of said platen toward the printing portions and 35 between said movements to cause transverse movements of the platen so that each printing portion may be inked by one pad while the article is being printed by the other printing portion.

6. A machine of the class described comprising ticket feeding means, printing means having two printing portions, said feeding means being operative to move a ticket along a generally zig-zag path between said printing portions, so that the ticket is first juxtaposed to one printing portion and then the other printing portion, said means moving the ticket into engagement with said portions when the ticket is moved into juxtaposition thereto, whereby the printing portions may alternately print the ticket, and operating 50 mechanism to cause the operation of the ticket feeding means.

7. A machine of the class described comprising ticket feeding means, printing means including a first and a second printing portion in side-by-side 55 relation, said feeding means being operative to move a ticket into engagement with said first portion and then to direct the ticket transversely and into engagement with said second portion, the feeding means thereafter being operative to 60 direct the ticket transversely and again into engagement with said first portion, whereby the first portion may print the ticket twice and the second portion may at least print the ticket once, and operating mechanism to cause the operation 65 of the ticket feeding means.

8. A machine of the class described comprising ticket feeding means, printing means including a first and a second printing portion in side-by-side relation, said feeding means being operative 70 to move a ticket into engagement with said first portion and then to direct the ticket transversely and into engagement with said second portion, the feeding means thereafter being operative to direct the ticket transversely and again into en- 75

gagement with said first portion, the feeding means then directing the ticket transversely and again into engagement with said second portion, whereby each of said portions may print the ticket twice, and operating mechanism to cause the operation of the ticket feeding means.

5 9. A machine of the class described comprising ticket feeding means, printing means including a first and a second printing portion in side-by-side relation, said feeding means being operative to move a ticket into engagement with said first portion and then to direct the ticket transversely and into engagement with said second portion, the feeding means thereafter being operative to 10 direct the ticket transversely and again into engagement with said first portion, the feeding means then directing the ticket transversely and again into engagement with said second portion, whereby each of said portions may print the ticket twice, and attaching means operable in synchronization with said feeding means, the latter being operative to direct a printed ticket from said second portion to the attaching means, said attaching means acting upon a printed ticket while 15 20 25 a succeeding ticket is being printed, and operating mechanism for actuating the feeding means and attaching means in synchronized relation.

10 10. A machine of the class described comprising ticket feeding means including a movable platen having a ticket supporting part and a movable feed finger, and a printing assembly having two printing portions, said platen being movable toward one of said portions to engage a ticket therewith and then moving away from 30 35 40 said portion while the feed finger moves over the platen to slide the ticket relative thereto, the platen thereafter being movable to engage the ticket with the other printing portion, and operating mechanism for causing the movement of the feeding finger and platen in synchronized relation.

40 11. A machine of the class described comprising ticket feeding means, including a strip feeding pawl, a movable platen and a feed finger, a knife, printing means having two printing portions arranged side by side, and operating means to drive said pawl, platen, finger and knife in synchronized relation so that said pawl advances a ticket strip to dispose the first ticket section on the platen, the knife thereupon severs the first 45 50 55 section to provide a separate ticket, the platen then moves the severed ticket into printing engagement with one of said portions and then transversely into printing engagement with said other portion, the finger moving over the platen and advancing the ticket during its transverse motion, the finger thereafter advancing the ticket until it passes off the platen.

55 12. A machine of the class described comprising ticket feeding means, including a strip feeding pawl, a movable platen and a feed finger, a knife, printing means having two printing portions arranged side by side, and operating means to drive said pawl, platen, finger, knife, and said mechanism in synchronized relation so that said pawl advances a ticket strip to dispose the first ticket section on the platen, the knife thereupon severs the first section to provide a separate ticket, the platen then moves the severed ticket into printing engagement with one of said portions and then transversely into printing engagement with said other portion, the finger moving over the platen and advancing the ticket during its transverse motion, the finger thereafter advancing the ticket until it passes off the platen 60 65 70 75 and to said mechanism.

13. A machine of the class described comprising ticket feeding means, including a strip feeding pawl, a movable platen having a ticket-receiving track and inking pads arranged at opposite sides of said track, a feed finger, a knife, printing means having two printing portions arranged side by side, and operating means to drive said pawl, platen, finger and knife in synchronized relation so that said pawl advances a ticket strip to dispose the first ticket section on the platen, the knife thereupon severs the first section to provide a separate ticket, the platen then moves the severed ticket into printing engagement with one of said portions and then transversely into printing engagement with 15 20 25 30 35 40 45 50 55 60 65 70 75 80 85 90 95 100 said other portion, the finger moving over the platen and advancing the ticket during its transverse motion, the finger thereafter advancing the ticket until it passes off the platen, one of said inking pads moving into engagement with one of said printing portions while the ticket-receiving track carries a ticket into printing engagement with the other printing portion.

14. A machine of the class described comprising ticket feeding means, including a strip feeding pawl, a movable platen and a feed finger, a knife, printing means having two printing portions arranged side by side, each including a set of printing wheels, the wheels of the two sets being arranged side by side and in axial alignment, said printing means being provided with common adjusting means capable of selectively adjusting any wheel of either set, and operating means to drive said pawl, platen, finger, and knife in synchronized relation so that said pawl advances a ticket strip to dispose the first ticket section on the platen, the knife thereupon severs the first section to provide a separate ticket, the platen then moves the severed ticket into printing engagement with one of said portions and then transversely into printing engagement with said other portion, the finger moving over the platen and advancing the ticket during its transverse motion, the finger thereafter advancing the ticket until it passes off the platen.

15. A machine of the class described comprising ticket feeding means, including a strip feeding pawl, a movable platen and a feed finger, a knife, printing means having two printing portions arranged side by side, an attaching mechanism, and operating means to drive said pawl, platen, finger, knife, and said mechanism in synchronized relation so that said pawl advances a ticket strip to dispose the first ticket section on the platen, the knife thereupon severs the first section to provide a separate ticket, the platen then moves the severed ticket into printing engagement with one of said portions and then transversely into printing engagement with said other portion, the finger moving over the platen to advance the ticket during its transverse motion, the finger thereafter advancing the ticket until it passes off the platen and to said mechanism, said mechanism being operable to attach a preceding ticket while the succeeding ticket is being printed, said pawl being arranged to engage a recess in each ticket section, said attaching mechanism being arranged to direct the point of a pin into such a recess of a ticket received by said mechanism.

16. A machine of the class described comprising ticket feeding means, including a strip feeding pawl, a movable platen and a feed finger, a knife, printing means having two printing portions arranged side by side, and operating means

- to drive said pawl, platen, knife and finger in synchronized relation so that said pawl advances a ticket strip to dispose the first ticket section on the platen, the knife thereupon severs the first 5 section to provide a separate ticket, the platen then moves the severed ticket into printing engagement with one of said portions and then transversely into printing engagement with said other portion, the finger moving over the platen 10 and advancing the ticket during its transverse motion, the finger thereafter advancing the ticket until it passes off the platen, said pawl being adjustable to feed either long or short tickets, said finger having the same path of movement 15 when feeding either a long or a short ticket.
17. A machine of the class described comprising ticket feeding means including a movable platen, printing means having first and second printing portions arranged side by side, said 20 platen being movable to cause a ticket carried thereby to move into printing engagement with the first of said portions, then to move the ticket transversely and then into printing engagement with the second of said portions, then to move the 25 ticket transversely and again into printing engagement with the first of said portions, and thereafter to move the ticket transversely and into printing engagement with said second portion, and means to cause the movement of the 30 platen, said means being adjustable so that the platen, while continuing to make all of the above-recited transverse movements, will only move the ticket into a single printing engagement with each of said printing portions.
- 35 18. A machine of the class described comprising ticket feeding means including a movable platen, printing means having first and second printing portions arranged side by side, said platen being movable to cause a ticket carried 40 thereby to move into printing engagement with the first of said portions, then to move the ticket transversely and then into printing engagement with the second of said portions, then to move the ticket transversely and again into printing 45 engagement with the first of said portions, and thereafter to move the ticket transversely and into printing engagement with said second portion, means to cause the movement of the platen, said means being adjustable so that the platen, 50 while continuing to make all of the above-described transverse movements, will only move the ticket into a single printing engagement with each printing portion.
19. A machine of the class described comprising 55 ticket feeding means including a movable platen, printing means having first and second printing portions arranged side by side, said platen being movable to cause a ticket carried thereby to move into printing engagement with the first of said portions, then to move the ticket transversely and then into printing engagement with the second of said portions, then to move the ticket transversely and again into printing 60 engagement with the first of said portions, and thereafter to move the ticket transversely and into printing engagement with said second portion, said feeding means also including a feeding 65 finger movable to advance the ticket slightly during each of the above-recited transverse movements, and means to cause the movement of the platen, said means being adjustable so that the platen, while continuing to make all of the 70 above-described transverse movements, will only move the ticket into a single printing engagement with each printing portion.

20. Printing method involving the employment of two sets of printing elements arranged side by side, said method comprising moving an article to be printed along a generally zigzag path between said portions, and into alternate engagement with said portions, whereby the printing by each of said portions may be duplicated. 5

21. A machine of the class described comprising a ticket feeding means, including a movable strip feeding pawl and a movable platen, a printing wheel assembly, a frame supporting the platen and assembly, and a knife to sever a ticket section advanced onto said platen by said pawl, said printing wheel assembly having a pivotal connection with the frame remote from 10 the platen so that the assembly may be swung away from the platen to afford access thereto and to the parts of the wheels that are normally juxtaposed to the platen.

22. A machine of the class described comprising ticket-feeding means, printing means including a platen and cooperating printing elements, attaching mechanism to apply an attaching element to a printed ticket, said printing means being arranged to print a ticket at substantially 20 the same time that the attaching mechanism is applying an attaching element to a preceding ticket, said attaching mechanism including means for feeding attaching elements to an attaching station, operating mechanism for actuating the feeding means, for causing relative movement of the platen and elements to printing position and for operating the attaching mechanism, and a manually controllable member 25 movable to a position to prevent relative movement of the platen and printing elements into printing position and to interrupt operation of the means for feeding attaching elements, while permitting continued operation of the portion of the attaching mechanism which applies attaching 30 elements to printed tickets, said member being movable from said position so that the operating mechanism may thereupon cause normal operation of the printing means and of the entire attaching mechanism. 35

23. A machine of the class described comprising ticket-feeding means including a ticket feeding pawl, a printing means including a platen and cooperating printing elements, attaching mechanism to apply an attaching element to a printed ticket, said printing means being arranged to print a ticket at substantially 40 the same time that the attaching mechanism is applying an attaching element to a preceding ticket, said attaching mechanism including means for feeding attaching elements to an attaching station, operating mechanism for actuating the feeding means, causing relative movement of the platen and elements to printing position and for operating the attaching mechanism, 45 and a manually controllable member movable to a position to prevent the pawl from moving through its strip feeding path and to prevent relative movement of the platen and printing elements to printing position as well as to interrupt operation of the means for feeding attaching elements, while permitting continued operation of the portion of the attaching mechanism which applies attaching elements to printed 50 tickets, said member being movable from said position so that the operating mechanism may thereupon cause normal operation of the pawl, the printing means and of the entire attaching mechanism. 55
